UNITED STATES PATENT OFFICE

148,651

DESIGN FOR A CONDIMENTS SHAKER

Milton Steele, Coral Gables, Fla.

Application October 24, 1946, Serial No. 134,202

Term of patent 14 years

(Cl. D44—22)

To all whom it may concern:

Be it known that I, Milton Steele, a citizen of the United States, residing at Coral Gables, in the county of Dade and State of Florida, have invented a new, original, and ornamental Design for a Condiment Shaker, of which the following is a specification, reference being had to the accompanying drawing, forming part thereof.

The figure is a perspective view of a condiment shaker, showing my new design.

I claim:

The ornamental design for a condiment shaker, as shown.

MILTON STEELE.
